(57) **CLAIM**

I claim the ornamental design for a serving plate, as shown and described.

DESCRIPTION

FIG. 1 is a top perspective view of the claimed design according to a first embodiment;

FIG. 2 is a second top perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a cross section view of the claimed design as shown in FIG. 3;

FIG. 10 is a top perspective view of the claimed design according to a second embodiment;

FIG. 11 is a second top perspective view thereof;

FIG. 12 is a top plan view thereof;

FIG. 13 is a bottom plan view thereof;

FIG. 14 is a front elevation view thereof;

FIG. 15 is a rear elevation view thereof;

FIG. 16 is a right side elevation view thereof;

FIG. 17 is a left side elevation view thereof; and,

FIG. 18 is a cross section view of the claimed design as shown in FIG. 12.

The ornamental design which is claimed is shown in solid lines in the Figures.
